UNITED STATES PATENT OFFICE.

ALOIS SCHайдHAUF, OF FRANKFORT-ON-THE-MAIN, GERMANY, ASSIGNOR TO
ROESSLER & HASSLACHER CHEMICAL COMPANY, OF NEW YORK, N. Y., A
CORPORATION OF GERMANY.

PROCESS FOR STABILIZING ALKALINE HYDROGEN-PEROXID SOLUTIONS.

1,181,409.

Specification of Letters Patent.

Patented May 2, 1916.

No Drawing.

Application filed May 1, 1913. Serial No. 764,738.

To all whom it may concern:

Be it known that I, ALOIS SCHайдHAUF, a subject of the Emperor of Germany, and resident of Frankfort-on-the-Main, Germany, have invented certain new and useful Improvements in Processes for Stabilizing Alkaline Hydrogen-Peroxid Solutions, of which the following is a specification.

This invention relates to a process for stabilizing hydrogen-peroxid in an alkaline solution.

Sodium-peroxid, or free hydrogen-peroxid, is much used for bleaching processes by first nearly or entirely neutralizing the alkali by a strong acid or by some suitable salt of neutral reaction, as for instance magnesium chlorid or calcium chlorid. Such processes have even been applied in those cases in which fibers offering great resistance to alkali have been subjected to bleaching.

It has been considered a settled fact that aqueous solutions of sodium-peroxid decompose most quickly at the usual temperature and especially at the high temperatures applied in bleaching processes. The same conditions prevail when an aqueous solution of pure hydrogen-peroxid is diluted to the proper concentration necessary for bleaching processes and for these purposes is furthermore rendered alkaline. Undoubtedly free caustic alkali exerts a strongly decomposing action on the hydrogen-peroxid, necessitating, in the case of using sodium-peroxid, the neutralization of the alkali by nearly or absolutely equivalent quantities of strong acid or suitable salts respectively. Such treatment causes the formation of an objectionable mud or sediment in the bath.

I have discovered that the decomposing action of the caustic alkali instead of forming mud or sediment in the bath during the process because of the addition of the considerable quantities of acid or compound respectively, may conveniently be counteracted by slight additions of a soluble magnesium salt, said compound being insufficient in quantity to cause the formation of any mud or sediment which in some way or other might play the part of a disturbing element; the results obtained by the use of soluble magnesium salts are even surpassed by magnesia or magnesium salts in combi-

nation with a suitable silica compound or 55 silicates.

The following experiments illustrate the efficiency of my new process:

1. 0.2 g. Na_2O_2 dissolved in 100 cc. of pure water heated for 1 hour at 85° C. had lost 60 all oxygen.

2. 0.2 g. Na_2O_2 in 100 cc. of water plus 0.015 g. crystallized waterglass had lost all oxygen after one hour.

3. 0.2 g. Na_2O_2 in 100 cc. of water plus 0.012 g. crystallized MgCl_2 showed, after being at 85° C. for 1 hour, still 40%, for 2 hours, still 10.7%, for 3 hours, still 3.8%, of the original amount of oxygen.

4. 0.2 g. Na_2O_2 in 100 cc. of water plus 0.015 g. of crystallized waterglass plus 0.012 g. crystallized MgCl_2 showed after 1 hour 48%, 2 hours 20%, 3 hours 10.3%, of the original amount of oxygen.

In many countries there may be water 75 which occasionally carries the amount of soluble magnesium salt or the silicon-magnesium compound necessary to stabilize the solutions of sodium-peroxid or to respectively counteract the decomposing influence 80 of the caustic alkali on the hydrogen-peroxid solutions. In such cases one need only dissolve the necessary quantity of sodium-peroxid and immediately obtains a stable alkaline bleaching bath. If the water 85 one has at disposal does not contain at all the constituents coming here into question, or if it does not carry the same in proper proportion, or if there is only one of the constituents present, one may quickly ascertain 90 by a simple experiment, which chemicals and what quantities of the same must be added to surely obtain the desired effect and where in the claims I refer to water 95 naturally containing in solution magnesia or magnesium salts or a suitable magnesium and silicon compound, I mean to include such whether they are all naturally present or but one of them is present and the other missing constituent must be added.

I do not restrict myself to any specific proportions nor to any particular chemicals further than those the appended claims demand.

I claim:

1. The process of stabilizing bleaching baths containing hydrogen peroxid in an alkaline solution consisting in adding to the

100

105

bath a soluble magnesium compound in a quantity insufficient to create a precipitate of mud in said bleaching bath.

2. The process of stabilizing bleaching baths containing hydrogen peroxid in an alkaline solution, consisting in adding to the bath a quantity of a soluble magnesium compound and proportionately of a soluble silicon compound, said quantity being insufficient to create a precipitate of mud in the bleaching bath.

3. The process of stabilizing bleaching baths containing hydrogen peroxid in an alkaline solution, consisting in adding to the bath a quantity of a soluble magnesium compound and proportionately of a soluble silicate, said quantity being insufficient to create a precipitate of mud in the bleaching bath.

20 4. The process of stabilizing bleaching baths containing hydrogen peroxid in an alkaline solution, consisting in adding to the bath a quantity of a soluble magnesium salt, and proportionately of a soluble silicate, said quantity being insufficient to create a precipitate of mud in the bleaching bath.

25 5. The process of stabilizing bleaching baths containing hydrogen peroxid in an alkaline solution, consisting in adding to the bath a quantity of a soluble magnesium salt 30 and proportionately of a soluble silicon compound, said quantity being insufficient to create a precipitate of mud in the bleaching bath.

6. The process for making a stable bath 35 containing hydrogen peroxid in an alkaline solution, consisting in dissolving sodium peroxid in water containing in solution magnesia, or magnesium salts.

7. The process for making a stable bath 40 containing hydrogen peroxid in an alkaline solution, consisting in dissolving sodium peroxid in water naturally containing in solution a suitable magnesium and silicon compound.

In testimony whereof I have signed my name to this specification in the presence of two subscribing witnesses.

ALOIS SCHайдHAUF.
